UNITED STATES PATENT OFFICE.

EUGENE H. LEWIS, OF ST. JOSEPH, MICHIGAN.

DESIGN FOR A BUILDING-BLOCK.

SPECIFICATION forming part of Design No. 20,242, dated October 28, 1890.

Application filed September 16, 1890. Serial No. 365,179. Term of patent 14 years.

To all whom it may concern: .

Be it known that I, EUGENE H. LEWIS, a citizen of the United States, and a resident of St. Joseph, in the county of Berrien and State 5 of Michigan, have invented a certain new and original Design for Building-Blocks, of which the following is a specification, reference being had to the accompanying drawings, forming a part hereof.

10 The leading feature of my design consists of a groove in one face of the block or brick, which extends longitudinally thereof and about midway between and parallel with the sides of said block, and a bevel extending 15 around all the edges of one face of the brick or block and having the ends of said longitudinal groove opening into and through said bevel.

In the drawings, Figure I is a perspective 20 view of a building-block showing my design. Fig. II is a cross-sectional view through the same, and Fig. III is an end elevation.

A designates the building block or brick, which is rectangular in form, and on the front 25 face a of said block I provide the bevel B, which is formed on all the side and end edges of the block and extends continuously around the same, the bevels at the angles or corners of the block being joined by the sloping lines 30 b b, which lie at angles to the lengths of the bevels. In the middle of the front face a of the block I provide the groove C, which extends longitudinally of the block and parallel with the side edges of the block and the bev-

els B on said side edges. This middle longitudinal groove has its sides made at an angle to each other, or it is V-shaped in cross-section, and the ends of said groove open or extend through the bevels at the ends of the block or brick, the terminals of the inclined 40 sides of said groove converging toward each other at the end bevels of the block and terminating in V-shaped incisions, as at c, which penetrate the end bevels.

The groove arranged centrally within the 45 bevels and parallel with the side edges of the block presents to the eye the appearance of two blocks or bricks when it is laid in conjunction with other bricks to form the wall.

Having thus described my invention, what I 50 claim is—

The design for a building-block herein shown and described, the same comprising the rectangular marginal bevel extending continuously around the edges of the block and the 55 longitudinal V-shaped groove or channel extending centrally along the face of the block parallel with the bevel at the sides of said block and having the ends of said groove or channel penetrating through the bevels at the 60 ends of said block, substantially as set forth.

In testimony whereof I affix my signature in presence of two witnesses.

EUGENE H. LEWIS.
